UNITED STATES PATENT OFFICE.

DIEUDONNE A. BEAUDRY, OF GILBERTVILLE, MASSACHUSETTS.

ELEVATOR.

1,335,719.

Specification of Letters Patent.

Patented Apr. 6, 1920.

Application filed October 24, 1919. Serial No. 332,939.

To all whom it may concern:

Be it known that I, DIEUDONNE A. BEAUDRY, a citizen of the United States, residing at Gilbertville, in the county of 5 Worcester and State of Massachusetts, have invented certain new and useful Improvements in Elevators, of which the following is a specification, reference being had to the accompanying drawings.

10 This invention relates to an improved elevator, adapted for freight or passengers, and has for its object to provide a very simple, efficient and practical device of this kind capable, when manufactured, of being produced at a relatively low cost and sold at a reasonable profit.

Another object of the invention is to provide an elevator, which may be operated by hand power, or by motor power, and wherein 20 ropes, gears, or plungers for the supporting and operation of the elevator car are eliminated, thereby greatly simplifying the construction of means for operating the car to ascend or descend.

25 A further object of the invention resides in the provision of means comprising opposite vertical tracks to be engaged by guides on the elevator car, in combination with a rotating member carried by the car having 30 a spiral thread including anti-frictional means adapted to operatively connect with the tracks, for causing the car to ascend or descend.

35 A still further object of the invention is to provide a safety operating mechanism for the car and carried thereby, to insure preventing the car from falling, as in the cases of other elevator cars heretofore used.

An additional object of the invention consists in applying the operating mechanism 40 to the car, on the body of the car itself, thereby not only simplifying the construction of such devices, but also facilitating the operation.

45 While the design and construction at present illustrated and set forth is deemed preferable, it is obvious that as a result of a reduction of the invention to a more practical form for commercial purposes, the invention 50 may be susceptible to changes, and the right to these changes is claimed, provided they are comprehended within the scope of what is claimed.

The invention comprises further features 55 and combination of parts, as will be here-

inafter set forth, shown in the drawings and claimed.

In the drawings:

Figure 1 is a view in front elevation of the improved elevator constructed in accordance with the invention, showing the guide tracks, and the elevator car in position and engaging them. 60

Fig. 2 is a view in side elevation of the elevator, illustrating the operating pulley and its connections with the rotating member on the inside of the body of the car, whereby the car may be caused to ascend or descend. 65

Fig. 3 is a vertical sectional view on line 3—3 of Fig. 2, showing the interior construction of the body of the car and also the rotating member therein, for operating the car. 70

Fig. 4 is a vertical sectional view on line 4—4 of Fig. 1, and 75

Fig. 5 is a horizontal sectional view on line 5—5 of Fig. 1.

Referring more especially to the drawings 1 and 2 designate vertically arranged parallel tracks, which are broad in cross section, and are provided on their adjacent faces with transversely arranged rack teeth 3. Mounted on and adapted to operate between the tracks is an elevator car 4, the lower portion or base body 5 of which is 30 hollow, and is adapted as a housing for the reception of the rotating member or car operating device 6. This rotating member or car operating device is mounted upon a shaft 7, the upper and lower ends of which 35 are mounted in ball bearings of the top and bottom of the housing or car base. This rotating member or car operating device 6 is provided with a spiral thread 9. The teeth of the adjacent faces of the tracks, are arranged or inclined as shown, to cooperate with the spiral thread of the rotating member or car operating device. It will be noted that the teeth of the adjacent faces of the tracks are so arranged relatively to each 40 other as to permit the spiral thread to pass from engagement with the teeth of one of the tracks, in engagement with the teeth of the opposite track, so that the rotating member or car operating device may readily operate to cause the car to ascend or descend. 45

The spiral thread of the rotating member or car operating device consists of a spiral band 10 secured to the rotating member or car operating device, on the periphery or 50

marginal edge of the member. This spiral band 10 is spaced radially from the rotating member or device, thereby affording sufficient space for the reception of the anti-frictional rollers 11. The pintles or shafts of these rollers are mounted in bearings of the band or rotating member, so that the rollers may freely rotate. The rollers are of sufficient diameters, so that they will project above and below the spiral band, so as to engage the teeth of the tracks. Furthermore the diameters of the rollers are sufficient to engage between the teeth of the tracks, for instance so that the rollers may rest upon and engage the teeth under them, without engaging the teeth above them, thereby permitting the rollers to very easily operate, without causing any undue friction, thereby allowing the car to easily and quickly ascend or descend.

The elevator car may be constructed preferably as shown, though not necessarily, for it is obvious that the car may be made as a cage affair, similar to the cars used on passenger elevators. Furthermore, the opposite sides of the car are provided with spaced vertical guide flanges 12, which engage on opposite sides of the guide tracks, thereby guiding the elevator car during its ascending or descending movements. In the present instance, however, the body of the car comprises the base part 4, the opposing sides 13 and the base platform 14, upwardly from which the sides 13 of the car rise. The forward and rear edges of the sides of the car have vertical braces 15 adjacent thereto but secured to the outer face of each side, to reinforce the sides. These vertical braces 15 are reinforced transversely by the transverse pieces 16, which are secured upon the outer faces of the car near their upper edges. The guide flanges 12 are secured to lateral projections 17, which extend from the upper portion of the outer faces of the sides 13 of the car and from the opposite sides of the base body of the car. The base body may be entirely closed in, to prevent access to the rotating member or car operating device, excepting when it is desired to lubricate the various parts. In order to permit access to the interior base body, one of the sides of the base body is provided with an opening 18, having a closure 19. Extending transversely of the elevator car and connecting the upper edge portions of the car is a brace 20 consisting of two parts, so as to reinforce the upper parts of the sides, at the same time holding the sides rigid.

Fixed to rotate with one of the pintles of the rotating member or car operating device there is a pulley 21, the groove 22 of which is engaged by an endless round belt or the like 23. The opposite parts of this belt extend laterally and substantially in parallelism, and are engaged over the pul-

leys 24, which are mounted upon the bearings 25 and 26. These bearings are preferably of the construction shown, though not necessarily, and one of the bearings is secured to the under face of the elevator car body, while another bearing is secured to the side, bottom end portion of the guide flanges of the elevator car body, thereby holding the pulleys in their proper positions.

A shaft 27 is mounted in a bearing of one of the sides of the elevator car body, and on one end of this shaft an operating pulley 28 is mounted. The other end of the shaft 21 is mounted in a bearing of a vertical strip 29, which arches the operating pulley 28. The endless round belt after passing over the pulleys adjacent the bottom or floor of the car body, passes over the pulley 28. When it is desired to cause the elevator car to ascend or descend, motion may be imparted to this shaft, thereby rotating the pulley 28, which in turn will operate the endless round belt, thereby imparting movement to the rotating member or device, through the medium of a groove roller on the wheel. It is obvious that any suitable power, such as a motor, gasoline or electric, may be geared to the shaft of the pulley 28, so as to impart motion thereto. For the convenience of illustration, simply a crank 31 is carried by the shaft, to impart motion thereto. When the rotating member or co-operating device is rotated, the spiral roller thread will feed into engagement with the opposite teeth of the tracks, thereby causing the car to ascend or descend. By means of the construction herein shown and described, it will be noted that elevator cars may be operated with safety, thereby preventing the car from falling or dropping, as in the cases where ropes, gears and plungers are employed for supporting and operating the car.

The invention having been set forth, what is claimed as new and useful is:—

1. In an elevator, the combination with vertical parallel tracks having opposed teeth spirally arranged, of an elevator operatively engaging said tracks, a member rotating in a horizontal plane and being carried by the car, said rotating member having a spiral anti-frictional thread engaging the teeth of the tracks, said spiral anti-frictional thread comprising a spiral band in surrounding relation to the periphery of the rotating member and being spaced therefrom, anti-frictional rollers journaled between the band and the periphery of the rotating member, and a driving-element carried by the car and being operatively connected with the rotating member for imparting motion thereto.

2. In an elevator, an elevator shaft having opposed parallel tracks provided with teeth spirally arranged, an elevator having

guides engaging said tracks, a drum mounted on the elevator for rotation in a horizontal plane, a band in spiral relation to the periphery of the drum, spaced journals engaging through the band and connected to the periphery of the drum to support the band in spaced relation to the periphery, a plurality of anti-frictional elements mounted upon the journals between the band and the periphery of the drum, and coöperating

5

with the teeth of the tracks for causing the elevator to move in a vertical plane in parallelism to the tracks, and driving means carried by the car of the elevator and operatively connected with the drum for imparting motion thereto.

In testimony whereof I hereunto affix my signature.

DIEUDONNE A. BEAUDRY.
